CLAIM

The ornamental design for an infant feeding device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of an infant feeding device.

FIG. 2 is a rear view thereof.

FIG. 3 is a left view thereof.

FIG. 4 is a right view of thereof.

FIG. 5 is a top view of thereof.

FIG. 6 is a bottom view of thereof.

FIG. 7 is a perspective view of thereof.

FIG. 8 is a front view of a second embodiment of an infant feeding device.

FIG. 9 is a rear view thereof.

FIG. 10 is a left view thereof.

FIG. 11 is a right view thereof.

FIG. 12 is a top view thereof.

FIG. 13 is a bottom view thereof; and,

FIG. 14 is a perspective view thereof.
